(57) CLAIM

The ornamental design for a game table, as shown and described.

DESCRIPTION

FIG. 1 is a perspective view of the game table.

FIG. 2 is a top view of the game table.

FIG. 3 is a front view of the game table; and,

FIG. 4 is a side view of the game table.

The broken lines of FIGS. 1-4 are included for the purpose of illustrating environmental structure and form no part of the claimed design.

1 Claim, 4 Drawing Sheets

FIG. 1

FIG. 4
